UNITED STATES PATENT OFFICE.

JOHN M. LUND AND HANS ANDERSON, OF BATTLEVIEW, NORTH DAKOTA.

DUSTPAN.

1,349,165.

Specification of Letters Patent. Patented Aug. 10, 1920.

Application filed June 4, 1920. Serial No. 386,480.

To all whom it may concern:

Be it known that we, JOHN M. LUND and HANS ANDERSON, said JOHN M. LUND being a citizen of the United States and said 5 HANS ANDERSON a subject of Norway, residing at Battleview, in the county of Burke, and State of North Dakota, have invented certain new and useful Improvements in Dustpans, of which the following is a specification.

10 This invention relates to a dust pan attachment for brooms, such as used in sweeping the floors of dwellings.

The principal object of the invention is 15 to produce a dust pan having a handle formed thereon which will readily engage a broom so that the dust pan may be hung thereon when not in use, and so that when said dust pan is thus hung it may be readily 20 pulled from engagement with the broom when it is desired to use same.

Another object of the invention is to produce a dust pan handle which is formed from a single strand of resilient wire, said strand 25 of wire being bent so as to form a plurality of jaws for embracing the handle of a broom.

A still further object of the invention is to generally improve upon devices of this 30 character by providing a device which will be extremely simple, durable and inexpensive in construction, one which is efficient and reliable in operation, and well adapted for the purpose for which it is designed.

35 With these and numerous other objects in view, the invention resides in certain novel features of construction, and combination and arrangement of parts as will be hereinafter fully described and claimed.

40 In the accompanying drawing:—

Figure 1 is a plan view of our invention, and

Fig. 2 is a longitudinal section taken therethrough.

45 In the preferred embodiment of our invention the dust pan 1 may be of any preferred construction although as shown it is concentric with the broom indicated in dotted lines in the figures so as to be readily placed thereover when not in use. The han-

50 dle, it will be seen, is formed of a single strand of wire which is bent over upon itself so as to form the bail indicated generally by the letter B. This bail B is bent at its top so 55 as to form the spring jaws 2 the belly of which is curved and forms a finger gripping

portion indicated by the numeral 3. The jaws 4 are formed on the bail B and are substantially parallel to the jaws 2 and are connected by means of the diagonal arm 5 as is clearly shown in Fig. 2 of the drawing. The jaws 4 are then bent over upon themselves so as to form the extension 6 extending at right angles from which are the legs 7 which penetrate through the rear edge of the dust pan and extend along the bottom of the dust pan 1 as is clearly shown in Fig. 2 of the drawing for a distance and are then curved so as to pass through apertures provided in the bottom of the dust pan 70 and to form the hooks 8.

From the above description it will be readily seen that by pulling outwardly upon the finger engaging extension 3 the handle may be easily pulled from engagement with 75 the handle of the broom. From the foregoing description, taken in connection with the accompanying drawing, the construction and operation of the device will be more readily understood without a more extended 80 explanation. As numerous changes in form, proportions, and in the minor details of construction may be resorted to without departing from the spirit of this invention, we do not wish to be limited to the construction 85 herein shown and described other than is claimed.

Having thus described our invention what we claim as new is:—

1. A dust pan comprising a handle formed 90 from a single strand of resilient wire so as to provide two pairs of parallel jaws connected by diagonal extensions, legs extending at right angles to one pair of said jaws so as to lie along the bottom of the dust pan. 95

2. A dust pan comprising a handle formed from a single strand of resilient wire so as to provide two pairs of parallel jaws connected by diagonal extensions, legs extending at right angles from one pair of said 100 jaws, so as to lie along the bottom of the dust pan, hooks formed on the ends of said legs so as to penetrate the bottom of said dust pan and hold said handle in place.

In testimony whereof we affix our signatures in presence of two witnesses.

JOHN M. LUND.
HANS ANDERSON.
